UNITED STATES PATENT OFFICE.

ROBERT M. WITMAN, OF EVANSVILLE, INDIANA, ASSIGNOR TO EVANSVILLE STOVE WORKS, OF EVANSVILLE, INDIANA, A CORPORATION OF INDIANA.

OVEN FOR COMBINATION COAL AND GAS RANGES.

1,191,379.

Specification of Letters Patent. Patented July 18, 1916.

Application filed November 5, 1915. Serial No. 59,775.

To all whom it may concern:

Be it known that I, ROBERT M. WITMAN, a citizen of the United States, residing at Evansville, county of Vanderburgh, and State of Indiana, have invented certain new and useful Improvements in Ovens for Combination Coal and Gas Ranges, of which the following is a specification.

This invention relates to ovens for combination coal and gas ranges.

My invention has for its object, more particularly, the provision of improvements in the oven of a gas range, but it is adapted for use in a combined coal and gas range so that all the advantages of the use of baking and broiling by the use of gas may be obtained without interfering with the heating of the oven by coal whenever such heating is preferred, the gas attachments being so constructed that they may be conditioned so they will be out of the way when not in use.

Another object is to provide novel improvements, applicable to a gas range alone or to a combination coal and gas range, whereby gas may be conveniently used for baking or broiling, and to that end, I provide a movable burner carrying baffle which is constructed and mounted in a novel manner so that it can be raised or lowered or set to be out of the way when gas is not to be used.

The invention also comprises a novel, duplex gas burner carried by a movable baffle and also novel air and gas mixers positioned at upper and lower points of the oven adapted to deliver the gas mixture to the burner when the baffle is in raised or lowered position.

Further improvements comprised in the present invention are the arrangement of the burners on the baffle, and the relationship thereto of a lighting aperture or orifice; and a flue provided with a damper and with an opening in the bottom of the oven to admit air to the oven whether used as a gas oven or a coal heated oven.

Other objects of the invention will appear more fully and at large from the following description of one embodiment of the different features of the invention, which, however, is to be considered as illustrative, rather than restrictive, of the scope of the invention, as modification may be resorted to in carrying out the different inventive ideas embodied therein.

In the accompanying drawings: Figure 1 is a front elevation with parts in section, the baffle being in its lower position; Fig. 2, a detail section on line 2—2, Fig. 1; Fig. 3, a plan view of the baffle, dotted lines representing the burners; Fig. 4, a detail vertical section from the front to the rear of the oven, the baffle being in its lower position; Fig. 5, a detail plan, partly in section, of one of the duplex mixers; Fig. 6, a front view of the same, showing the air dampers or valves; Fig. 7, a horizontal section through the burner; Fig. 8, a detail view showing the enlargements of the header; and Fig. 9, a diagram of a modification.

In the drawings only so much of a gas and coal range is shown as will give a clear understanding of my improvements which relate solely to the oven 1. In the bottom of the oven is an aperture 2 which is one end of a flue 3 leading to the side thereof and provided with a damper 4. When the oven is heated by gas, the damper 4 is opened to permit air to enter the oven in suitable volume to aid in the combustion of the gas. When the oven is heated by coal, the damper 4 will be closed.

At one side of the oven in convenient position for manipulation and adjacent the bottom and top thereof, are duplex gas and air mixers 5 and 6, each of which is of the detailed construction shown in Figs. 5 and 6. These duplex air and gas mixers have two conduits or inlets 7 and 8 provided with the air regulating dampers or caps 9, commonly used in gas admission fixtures. The conduits 7 and 8 converge to opposite sides of a partition 10 contained within the nipple 11 which is designed to enter the end of the burner as will presently appear. For each of the inlets 7 and 8 there is provided a gas admission cock 12 and 13 entering centrally through the air regulating dampers 9. Means are thus provided whereby a partial flow of gas and air may be introduced into the conduits 7 and 8, or into only one of them, or a full supply into both.

The baffle 14 is provided with studs 15 and 16 which are preferably incased in rollers 17. The baffle is also provided with lugs 18 at its sides, near its front edge. The duplex burner shown in detail in Fig. 7 is connected to, and bodily carried by, the baffle 14, this burner being secured to the bottom face of the baffle. The burner comprises

duplex burner tubes 19 and 20, each having numerous perforations, as usual, and provided with a central partition 21. The header 22 has a central partition 23 and a cross-partition 24. The partition 23 has a perforation or port 25. The partitions 21 run up to and join the partition 23. In the region of the cross-partition 24, one portion of the header 22 is enlarged above and below, as at 26 and 27, to permit the passage of the gas to the other burner 20. As shown by the arrows, Fig. 7, it will be apparent that gas entering the compartment 28 of the header 22, will flow into the left-hand side of the burner 19 and the right-hand side of the burner 21, and gas entering the compartment 29 will only enter the right-hand side of the burner tube 19 and the left-hand side of the burner 20. The control of flow of the gas to the burner tubes 19 and 20 is accomplished by operating the valves 12 and 13 and by this means either a small or a large degree of heat can be obtained. The nipples 11 of the respective duplex burners 5 and 6 are arranged to enter the end 30 of the header 22, according as the baffle 14 is in lowered or raised position, such nipples 11 being adapted to bear against a washer 31 within the nipple 30, and the partitions 10 and 23 being arranged so that they will come into alinement when the burner is coupled to either one of the duplex mixers. Consequently, one of the valves 12, for instance, solely controls the admission of gas and air to the compartment 28 and the other valve, say 13, controls the admission of gas to the compartment 29.

To light the burners, there is provided an aperture 32 in the baffle 4, through which a match may be introduced after the gas has been turned on.

Secured to the sides of the oven and projecting a slight distance inwardly therefrom for the purpose of coöperating with the studs 15, 16 and 18, are the supports 33, one being provided for each side of the oven and these being duplicates. Each support has two V-shaped guides or tracks 34 and 35, in which the studs 15, 16 and rollers 17 are adapted to travel. The lower ends of these guides or tracks are disposed horizontally at 36 and at the front there is provided a notched portion 37 to receive the studs 18. At the tops of the supports 33 the guides 34 and 35 open out and at the back there are provided the recesses 38 to receive the studs 15, 16 and rollers 17. At the top and front there are two notches 39 and 40 into either of which the studs 18 may be entered. At the apices of the tracks 34 and 35 horizontally enlarged or extended parts of said guides are provided at 41 and 42.

When it is desired to use the gas burner for baking purposes, the lugs 18 rest in the notches 37 and the lugs 15 and 16 in the

horizontal extensions 36. When it is desired to place the baffle in the upper part of the oven, particularly for broiling purposes, the front edge of the baffle is grasped and pulled outwardly in relation to the oven, whereupon the lugs 15 and 16 travel upwardly in the channels or guides 34 and 35 until they reach the extensions or enlargements 41 and 42. Then, by a slight downward manipulation of the baffle and an inward and upward pressure, the lugs will enter the upper portions of the channels 34 and 35 and afterward the baffle can be pushed back until the rear lugs 15 enter the recess 38 and the lugs 16 rest on the part 43. The lugs 18 will then enter the notches 39. The baffle plate will then remain securely in its raised position until it is desired to lower it again for gas baking purposes.

The notches 40 are provided for the reception of the lugs 18 when it is desired to broil with gas, but to get the baffle plate out of the way so that the oven may be heated by coal, the baffle is pushed back and the lugs 18 enter notches 39. When the baffle is pulled forward and lugs 18 enter notches 40, the nipple 11 of the upper mixing device 6 becomes connected with the nipple 30, as the nipple 11 is long enough for that purpose. In its raised and lowered positions, the baffle will be so disposed that the nipple 30 will connect with the nipple 11 of either one of the upper or lower duplex mixers 6 and 5. The gas pressure prevents any leakage, as well known in gas fixtures. At points intermediate between the duplex mixers, the gas of the burner is completely disconnected from said mixers.

In the modification shown diagrammatically in Fig. 9, the guiding supports at the sides of the oven are duplex, being composed of the lower guides 44 and the upper guides 45. The upper air and gas mixer 6 is located midway the height of the oven so that the baffle 4 may be positioned and supported for broiling with gas midway the height of the oven, as shown in full lines in said figure, thus providing a smaller broiling oven. The baffle 4 will be disposed in the upper dotted line position, out of the way, only when coal, wood or coke is used for cooking. In this form the device 6 need not be used at the top of the oven.

My improved duplex burner comprising the parts 19, 20, 22, as shown and described, can be permanently attached to a gas range or oven when not used in a combination gas and coal range. In that event, the baffle and means for guiding and supporting it could be dispensed with.

Having thus described my invention, what I claim as new and desire to secure by Letters Patent is:—

1. The combination with an oven, of a baffle slidable inwardly and outwardly in

the oven and movable from a lower to a higher point in the oven, a gas burner carried by, and bodily movable with, said baffle, and separate means for supplying gas to 5 said burner when in different positions in said oven, said burner being disconnected from said gas supplying means when slid outwardly and also when being moved from one position to a higher or lower position 10 in the oven.

2. The combination with an oven, of a baffle movable from the bottom to the top of the oven, a gas burner carried by, and bodily movable with, said baffle, and gas 15 supplying devices arranged and adapted to independently connect with, or disconnect from, the burner when it is at the lower and at a higher position in said oven, said burner being disconnected from said gas supplying 20 devices when being moved from one position to another in said oven.

3. In an oven, the combination with tracks or guides at the sides thereof, of a movable baffle, a gas burner carried thereby, means 25 on the baffle adapted to travel in said tracks or guides, whereby the baffle may be arranged at the bottom or at a higher position in the oven and shifted from one position to the other and separate gas supplying 30 devices arranged to independently connect with, or disconnect from, said burner when the baffle is in different positions in the oven.

4. In an oven, the combination with tracks 35 or guides having branches disposed angularly to each other at the sides thereof, of a movable baffle, a gas burner carried thereby, and means on the baffle adapted to travel in said tracks or guides, whereby the 40 baffle may be arranged at the bottom or at

a higher position in the oven and shifted from one position to the other.

5. In an oven, the combination with substantially V-shaped tracks or guides at the sides thereof, of a movable baffle, a gas 45 burner carried thereby, and means on the baffle adapted to travel in the V-shaped guides, whereby the baffle may be disposed in lower or upper positions in the oven by manipulation and will have its movements 50 controlled by said guides when shifting from one position to another.

6. In an oven, the combination with a baffle which is movable inwardly and outwardly in said oven, of a burner carried 55 thereby, and a gas supplying device with which said burner is adapted to connect when in one of said positions and from which it becomes detached when moved to its other position. 60

7. In an oven, the combination with tracks or guides at the sides thereof, of a baffle, a gas burner carried by the baffle, said baffle having means adapted to engage said guides, whereby it may be disposed in upper or 65 lower positions, means for retaining the baffle in its lower position, and means for retaining the baffle in pushed-in or pulled-out condition when in its upper position.

8. In an oven, the combination with tracks 70 or guides at the sides thereof, of a baffle, a gas burner carried by the baffle, said baffle having means adapted to engage said guides, whereby it may be disposed in upper or lower positions, and rests for retaining the 75 baffle in its lower and upper positions.

In testimony whereof, I hereunto affix my signature.

ROBERT M. WITMAN.
